UNITED STATES PATENT OFFICE.

BENJAMIN W. MAY, OF CHICAGO, ILLINOIS, ASSIGNOR TO THE SCHWARTZ-KOPFF COAL DUST FIRING COMPANY, OF CHICAGO, ILLINOIS, A CORPORATION OF ILLINOIS.

APPARATUS FOR BURNING COAL-DUST.

SPECIFICATION forming part of Letters Patent No. 746,864, dated December 15, 1903.

Application filed November 2, 1900. Serial No. 35,226. (No model.)

To all whom it may concern:

Be it known that I, BENJAMIN W. MAY, a citizen of the United States, residing at Chicago, in the county of Cook and State of Illinois, have invented a new and useful Apparatus for Burning Coal-Dust, of which the following is a specification.

This invention relates to an apparatus for burning coal-dust, and is designed as an improvement upon the construction set forth and claimed in Patent No. 558,875, issued April 21, 1896, and reissued April 3, 1900, re-issue No. 11,816, to Georg Hilliger.

The object of the invention is to provide a construction adapted for use in feeding or delivering coal-dust or similar fuel into the combustion-chamber and the proper distribution thereof to secure complete combustion.

A further object is to provide a construction wherein the coal-dust or other fuel is fed into the combustion-chamber in a continuous evenly-distributed stream.

Other objects of the invention will appear more fully hereinafter.

The invention consists, substantially, in the construction, combination, location, and arrangement, all as will be more fully herein-after set forth, as shown in the accompanying drawings, and finally pointed out in the appended claims.

Referring to the accompanying drawings, Figure 1 is a view in vertical section of an apparatus for feeding coal-dust embodying the principles of my invention. Fig. 2 is a detached detail broken view in perspective of the steam or air jet nozzle. Fig. 3 is a similar view showing a slightly-modified arrangement of the same.

In the patent to Hilliger above mentioned is set forth, described, and claimed an apparatus for feeding coal-dust comprising a hopper and a brush-casing having a delivery-opening, and a shaking device above the brush-casing with means for actuating the same, and a rotary brush in the casing adapted to act on the material released by the shaking device to deliver the same into the furnace-chamber.

In the operation of an apparatus embodying these principles of construction the fuel,

in the form of dust, is placed in the hopper and is delivered therefrom into the furnace-chamber in a continuous uniform evenly-distributed stream by means of the rotary brush, the brush flicking or projecting the particles of dust into the furnace-chamber and the shaking device not only serving to prevent clogging of the hopper, but also operating to shake or jar the dust down into position to be engaged by the brush and projected thereby into the furnace-chamber.

The particles of dust delivered in the manner set forth and in a continuous evenly-distributed stream become ignited and are consumed while remaining suspended within the furnace-chamber, thereby generating an intense heat, the continuous and uniform feed of the dust serving to maintain such heat, thereby obtaining a marked degree of efficiency in steam production and great economy in fuel-supply by reason of the complete combustion of the coal or other fuel.

The present invention relates to an apparatus of this nature and type and contemplates as the essential feature thereof the substitution of an air, steam, or gas jet for the brush as a means for projecting the particles of dust into the combustion-chamber. By employing a steam, air, or gas jet through which a continuous stream or sheet of air, steam, or other gas is forced into the chamber at the point of delivery of the coal-dust fuel not only will such fuel be supplied to the chamber in a continuous, uniform, and evenly-distributed stream, but the particles thereof will be sufficiently supported or suspended in the combustion-chamber and will be moved or carried through the combustion-chamber a greater distance than would otherwise be the case, thereby insuring a complete combustion thereof, and hence gaining the advantage and utilization of the calorific power of every particle of the fuel in the production of heat.

Referring to the construction illustrated in the accompanying drawings, reference-sign A designates the hopper in which the coal-dust or similar fuel is placed. Suitably hinged within the hopper or casing B is a plate C. Spring D, the tension of which may be read-

ily adjusted, as by means of the nut E, is arranged to bear against plate C. Carried by the plate C is a stud or projection F, arranged to bear against a cam G, carried by a shaft or stud H, adapted to receive rotation in any suitable or convenient manner. The springs D serve to maintain constant engagement or bearing of stud F against the cam-surface. Therefore when rotation is imparted to shaft H a vibratory movement is imparted to plate C. Associated and coöperating with plate C is a spring-plate J, connected by links K to plate C.

From the foregoing description it will be seen that when the cam G is placed in operation a rapid vibratory movement is imparted to the plates C and J, thus constituting a shaking device adapted to alternately confine and release the coal-dust contained in the hopper or casing B, and hence preventing the coal-dust from clogging such hopper or casing and permitting the same to be fed or deposited upon the portion L of the plate C or other suitable surface, which preferably is inclined toward the combustion-chamber. In order to regulate the feed of the coal-dust under the action of the shaking device, a plate M is employed, said plate being carried by a rocking support actuated by a handle or lever N, the said controlling-plate M coöperating with the shaking device C to provide more or less of an opening when plate C is vibrated to permit the coal-dust or similar fuel to pass from the hopper or casing B for delivery into the combustion-chamber. O designates a nozzle for an air, steam, or gas jet, the mouth or opening P of said nozzle being located immediately below the point of delivery of the coal-dust from the shaking device. Thus in the particular construction illustrated the mouth or opening P of the nozzle is located at a point immediately below the delivery edge of the platform or apron L, and when the device is in operation and a continuous sheet or stream of air, steam, or gas is delivered through the nozzle the coal-dust delivered by the shaking device will be projected by such jet into the combustion-chamber, the jet forming not only a carrier for the particles of coal-dust, but also serving to maintain the same suspended within the combustion-chamber until complete combustion thereof is secured, and when an air-jet is employed a supply of oxygen is secured which aids materially in the production of complete combustion, and hence the generation of a very great heat within the combustion-chamber. In order to secure the best results, I prefer to arrange the nozzle O in a slightly-inclined position, so as to give to the sheet or jet of air or the like a slightly-vertical projection into the furnace-chamber.

The cam or other means for imparting movement to the shaking device and the supporting shaft or stud therefor should be arranged at a point so as not to interfere or to be in line with the projection of the dust under the influence of the air-jet, and it is obvious that

such cam or other suitable actuating apparatus for the shaking device may be arranged at any suitable or convenient point. It is also obvious that the specific construction of the shaking device may be altered or varied without departure from the spirit or scope of my invention.

I prefer to employ a nozzle having a continuous mouth or opening P, which extends the full width of and in parallel relation to the point of delivery of the dust from the shaking device; but it is obvious that, if desired, a nozzle or jet having a series of orifices or openings P' may be employed and still fall within the spirit and scope of the invention. (See Fig. 3.)

Having now set forth the object and nature of my invention and a construction embodying the principles thereof, what I claim as new and useful and of my own invention, and desire to secure by Letters Patent, is—

1. In an apparatus for feeding coal-dust, a hopper A, a shaking-plate C hinged at the mouth thereof and means for reciprocating the plate C, a normally stationary plate M having its edge extended toward the plate C, and a pressure chamber or box having an opening or openings extending continuously along its front side to constitute a nozzle O, adjacent to the plate C, whereby a substantially uniform sheet of dust is dropped into a substantially uniform sheet of projected air or steam, as and for the purpose set forth. 100

2. In an apparatus for feeding coal-dust, a hopper A, a shaking-plate C hinged at the mouth thereof and means for reciprocating the plate C, a normally stationary plate M, but adjustable, having its edge extended toward the plate C, and a pressure chamber or box having an opening or openings extending continuously along its front side to constitute a nozzle O, adjacent to the plate C, whereby a substantially uniform sheet of dust is dropped into a substantially uniform sheet of projected air or steam, as and for the purpose set forth. 110

3. In an apparatus for feeding coal-dust, a hopper A, a shaking-plate C hinged at the mouth thereof and means for reciprocating the plate C, a normally stationary plate M, but adjustable, having its edge extended toward the plate C, and an upwardly-deflected pressure chamber or box having an opening or openings extending continuously along its front side to constitute a nozzle O, adjacent to the plate C, whereby a substantially uniform sheet of dust is dropped into a substantially uniform sheet of projected air or steam, 125 as and for the purpose set forth.

In witness whereof I have hereunto set my hand, this 26th day of October, 1900, in the presence of the subscribing witnesses.

BENJAMIN W. MAY.
